FIG. 1 is a front elevational view of a portion of an overhead garage door façade in a closed configuration showing my new design;

FIG. 2 is a front elevational view thereof in a partially open configuration;

FIG. 3 is a front elevational view of a portion of an overhead garage door façade in a closed configuration showing another embodiment of my new design; and,

FIG. 4 is a front elevational view thereof in a partially open configuration.

The broken line showing of the handles is for illustrative purposes only and forms no part of the claimed design. The broken line showing of the garage building structure in FIGS. 1 through 4 and the vehicles shown in FIGS. 2 and 4 are for illustrating an environment of the design and form no part of the claimed design.
